UNITED STATES PATENT OFFICE.

GODFREY M. S. TAIT, OF MONTCLAIR, NEW JERSEY, ASSIGNOR TO TAIT PRODUCER COMPANY, OF NEW YORK, N. Y., A CORPORATION OF NEW JERSEY.

PROCESS OF GENERATING AND UTILIZING PRODUCER-GAS.

1,175,191.

Specification of Letters Patent. Patented Mar. 14, 1916.

Application filed January 11, 1910. Serial No. 537,381.

To all whom it may concern:

Be it known that I, GODFREY M. S. TAIT, a subject of the King of England, and a resident of Montclair, in the county of Essex and State of New Jersey, have invented certain new and useful Improvements in the Process of Generating and Utilizing Producer-Gas, of which the following is a full, clear, and exact specification, such as will enable others skilled in the art to which it appertains to make and use the same.

My invention relates to a process of generating and utilizing producer gas, particularly, though in some aspects not necessarily, in connection with gas engine power plants.

The object of the invention is to increase the effective gasifying action and to produce a gas from bituminous coal or mixture of such coal and hydrocarbon oil comparatively free from tar and similar unfixed hydrocarbons.

It is further an object of the invention to adapt a gas engine to the producer in such a manner that the gas will be drawn by suction from the producer and an approximately equal pressure applied to the draft current, thus bringing about a state of balanced pressures within the producer greatly facilitating practical operation thereof.

My invention involves various other features of advantage, the practical attainment of all of which depends upon certain novel steps in treatment of the fuel and gas and all of which will be fully set forth herein-after and particularly pointed out in the claims.

For the purpose of plainly illustrating the practice of my process, reference is made to the accompanying drawings which show an apparatus designed to carry out the same.

In these drawings:—Figure 1 represents an elevational view of the gas producer power plant in which the producer itself is shown in section; Fig. 2 illustrates an enlarged sectional view of an injector which may be employed to bring about the pressure condition in an ash pit of the producer as will fully appear hereinafter; and Fig. 3 is a plan view of such injector.

It will first describe the mechanical organization of the plant illustrated in said drawings so that the subsequent description of my improved process may be more readily understood.

Referring, therefore, to the drawings, 10 indicates the body of the producer which is here shown as brick-lined and furnished in its upper portion with a coking chamber 11 of fire brick or other refractory non-conducting material. This coking chamber is 60 open at its bottom and is supported on a series of piers 12 which project inward from the walls 10 of the producer and engage the walls 11 of the coking chamber. The top 14 of the producer is provided with a 65 series of poke holes 15 and 16 which allow the interior of the producer both inside and outside of the coking chamber to be reached. The producer is here shown as of what I have termed the balanced draft type, i. e., 70 in which the ash pit 17 is designed to receive a draft current under pressure and in which an outlet or discharge 18 is provided through which the gases are drawn off and suction exerted in the gas line 19. The gas line 19 passes to the scrubber 20 and the gas from the scrubber is discharged by a connection 21 to the purifier 22. From there it is conducted, preferably, though not necessarily, under the suction of a four-stroke cycle gas 80 engine, through a pipe 23 to the engine 24. The exhaust from the engine passes through a pipe 25 to an outlet 26 to the atmosphere. A part of the exhaust gases is taken off through a branch connection 26' and led into 85 an injector, the preferred details of which are shown in Figs. 2 and 3. Referring to these figures, 27 indicates a valve to which the branch connection 26 leads, and 28 indicates a valve controlling communication 90 with the atmosphere. The valve 27 discharges into an injector nozzle 29 which in turn discharges into the throat of the injector. Said throat communicates with the atmosphere through the valve 28 and the 95 throat discharges into the ash pit of the producer. The pressure of the exhaust causes the injector action to take place and in this manner sufficient air is thrown into the ash pit to supply the necessary draft current supporting the combustion in the producer and also to supply sufficient pressure in this draft current to balance the suction at the discharge 18 as will hereinafter fully appear.

In Fig. 1, 31 indicates a jet device for air or steam which may be employed as an auxiliary to increase the pressure in the exhaust

line 25; and 32 in said view indicates means for supplying steam or water to the draft current as an endothermic agent should such be necessary or desirable. 33 indicates a means for supplying a liquid hydrocarbon to the fuel in the coking chamber. By means of the valves 27 and 28 of the injector the pressures and proportions involved may be regulated as required.

10 Assuming the use of such an apparatus for practising my process the various steps or operations of such process are as follows: Upon starting the operation of the producer and the evolution of heat therein, gas is formed in the incandescent zone in the lower part of the producer and up to a point at the lower portion of the coking chamber, in accordance with the familiar reactions involved with the chemical combination of carbon and oxygen. This gas passes between the piers 12 and out of the producer. Simultaneously the heat in the coking chamber drives off the volatile hydrocarbon gases of the green coal and these gases, having no outlet at the top, are forced downward through the upper portion of the incandescent fuel zone and out around the lower edges of the coking chamber. The gases thus given off from the green coal are heavy unfixed hydrocarbon gases bearing a large quantity of tarry matter. As such gases pass through the fire they are finely sub-divided in passing through this heated porous material and their hydrocarbon content is cracked or fixed by the action of the heat when so sub-divided and the gases reform as fixed illuminants and then mingle with the gases formed in the lower part of the producer, which I have described. The mixture of all of the fixed gases passes out through the scrubber and purifier and then to the engine. This operation takes place in the absence of air so that the gases from the coking chamber cannot burn. In order to enrich the gas with hydrocarbons, if conditions requiring such enrichment, hydrocarbon oil may be supplied with the coal. This oil will be vaporized by the heat and the vapors thus formed will undergo the same operation as that undergone by the gases from the coking chamber. In the engine the gases from the producer are burned to produce power in the manner characteristic of the operations in a four-stroke cycle or other internal combustion engine. The exhaust gases from the engine pass, under pressure, through the pipe 25, some of such gases going out of the exhaust vent 26 and a comparatively small proportion of such gases being taken away through the connection 26' to the injector where they are utilized to draw in the air necessary in the draft current of the producer and to supply the pressure in the ash pit, as I have explained. It will be seen, therefore, that

I supply the draft current to the producer under a pressure which is above atmosphere to an extent substantially proportional to the minus or suction pressure below atmosphere in the outlet 18. For example, if the pressure of the draft current at the ash pan is equal to $\frac{1}{2}$ inch water column pressure then the suction in the gas outlet should be equal to $\frac{1}{2}$ inch water column partial vacuum. This results in establishing atmospheric pressure within the producer at a point where the plus and minus pressures equalize or balance. This allows operating the producer under easy pressure conditions and enables me to open the producer at any time for poking or inspection of its operation without bringing about an escape of air or gas either into or from the producer. It will also be apparent that by adjusting the valves 27 and 28, I can vary the point in the fuel bed at which this equalization of pressure takes place; restriction of opening of these valves causing the point of equalization to be relatively low down in the fuel bed, and wider opening of these valves causing the point of equalization to be higher up in the fuel bed. This ability to vary the point of equalization of pressures is very convenient in regulating the action of the producer; and it is also desirable to shift the point of equalization to a point well down in the fuel bed, preliminary to poking or cleaning the fuel bed.

The manner in which the pressure in the draft current is supplied by the exhaust from the internal combustion engine renders the operation of the system entirely automatic and self-regulating. As the load on the engine increased and a correspondingly increased demand for gas occurs, the suction in the outlet 18 will be increased. Simultaneously the exhaust pressure of the engine will be increased so that therefore the pressure rises in the exhaust current correspondingly with the increase in suction in the outlet 18. As the engine slows down and its operation becomes less vigorous, these conditions will be correspondingly altered; the suction will decrease and the force of the pressure draft will also fall.

The exhaust gases are not introduced into the producer as an endothermic agent; they are employed purely for the purpose of securing a means by which pressure may be created in the draft current. For this purpose they are particularly advantageous because, as I have pointed out, the system becomes self-regulating. If an endothermic agent is necessary in the draft current, such agent may be supplied by a steam jet at 31 or other water stream from which vapor is generated at the point 32. The quantity of carbon dioxide introduced into the draft current in accordance with my process is

practically inappreciable. In practice it will fall as low as 1 to 1½% and rarely rises above 2 to 2½% by volume at that temperature which in a sample cooled to say 60° F. 5 would show but a trace of CO₂. This carbon dioxid content therefore is not present in the draft current to an extent sufficient to deter combustion in the fuel bed or otherwise to have appreciable influence on the 10 operation of the process.

Having thus described my invention, what I claim as new and desire to secure by Letters Patent of the United States, is:

1. The process of making producer gas 15 comprising supplying fuel and draft current to a producer and maintaining incomplete combustion of said fuel and creating a suction or rarefied state at the outlet side of the producer by the suction of a gas 20 engine and a pressure condition at the draft side of the same by the pressure of the exhaust of said engine and in regulating such conditions automatically to cause the said pressures to balance or equalize at a point 25 within the fuel bed of the producer.

2. The process of making producer gas, which comprises maintaining a bed of incandescent fuel of effective gasifying depth, supplying air under pressure greater than 30 that of the atmosphere to one side of said fuel bed, and drawing off the gas produced from an intermediate point of said fuel bed, under less than atmospheric pressure, and thereby causing the pressures to balance 35 or equalize at a point within the fuel bed of the producer, distilling hydrocarbon gases from the fresh fuel of said fuel bed and causing said evolved gases to pass through the incandescent portion of said bed and to mingle 40 and be drawn off with the gas formed in said fuel bed by the incomplete combustion of the fuel with the air, whereby such hydrocarbon gases are drawn off by the suction which draws off the producer gas and

are fixed by their passage through the in- 45 candescent portion of said bed.

3. The process of making producer gas, which comprises maintaining a bed of incandescent fuel of effective gasifying depth, supplying a combustion supporting medium 50 to one side of said fuel bed, and drawing off the gas produced from an intermediate point of said fuel bed, supplying liquid hydrocarbon to a moderately heated portion of said fuel bed, and causing said hydrocarbon in a vaporized form to pass through the incandescent portion of said bed and to mingle and be drawn off with the gas formed in said fuel bed by the incomplete combustion of the fuel with air, whereby such 60 liquid hydrocarbon is converted into a fixed gas and is drawn off with the producer gas.

4. The process of making producer gas, which comprises maintaining a bed of incandescent fuel of effective gasifying depth, 65 supplying air under pressure greater than that of the atmosphere to one side of said fuel bed, and drawing off the gas produced from an intermediate point of said fuel bed, under less than atmospheric pressure, and thereby causing the pressures to balance or 70 equalize at a point within the fuel bed of the producer, supplying liquid hydrocarbon to a moderately heated portion of the fuel bed and to mingle and be drawn off with the 75 gas formed in said fuel bed by the incomplete combustion of the fuel with air, whereby such liquid hydrocarbon is converted into a fixed gas and is drawn off with the producer gas.

In testimony whereof I have signed my name to this specification in the presence of two subscribing witnesses.

GODFREY M. S. TAIT.
